Color Photographs of BP Fuel Station Canopy Considered to be Prior Art.

Primary Examiner—Louis S. Zarfas

Assistant Examiner—Monica A. Weingart

CLAIM

The ornamental design of a service station canopy, as shown.

DESCRIPTION

FIG. 1 is a perspective view of a first embodiment of service station canopy in accordance with the present design;

FIG. 2 is a front view of the service station canopy of FIG. 1;

FIG. 3 is a top view of the service station canopy of FIG. 1;

FIG. 4 is a side view of the service station canopy of FIG. 1;

FIG. 5 is a perspective view of a second embodiment of a service station canopy in accordance with the present design in which the peripheral edge of the canopy is ornamented in a contrasting color to the bottom surface of the canopy;

FIG. 6 is a front view of the service station canopy of FIG. 5;

FIG. 7 is a top view of the service station canopy of FIG. 5; and,

FIG. 8 is a side view of the service station canopy of FIG. 5.

The back view of the service station canopy of FIG. 5 is the same as the front view (FIG. 6).

In a third embodiment of the design (illustrated in FIGS. 5-8), the peripheral edge of the canopy is ornamented in red.

The dotted lines showing the fuel pumps and a building are for environmental purposes only and form no part of the claimed design.
